DESIGN FOR A TOE RING

Joseph Shapiro, New York, N. Y., assignor to Joseph Shapiro and Abraham Gluck, doing business as Eto Ring Co.

Application December 30, 1947, Serial No. 143,440

Term of patent 14 years

(Cl. D45—10)

To all whom it may concern:

Be it known that I, Joseph Shapiro, a citizen of the United States of America and a resident of the city of New York, in the county of the Bronx and State of New York, have invented a new, original, and ornamental Design for Toe Ring, of which the following is a specification, reference being had to the accompanying drawing,
forming a part thereof.

showing my design.

Figure 4 is a side view thereof.

I claim:

The ornamental design for a toe ring, substantially as shown.

JOSEPH SHAPIRO.
